(57) **CLAIM**

The ornamental design for a package for heat dissipating cream, as shown and described.

DESCRIPTION

FIG. 1 is a perspective view of a package for heat dissipating cream showing my new design.

FIG. 2 is a right side view thereof.

FIG. 3 is a front elevational view thereof.

FIG. 4 is a left side view thereof.

FIG. 5 is a rear elevational view thereof.

FIG. 6 is a perspective view thereof, with a cap in closed condition; and,

FIG. 7 is a perspective view thereof, in an exploded condition.
